CLAIM

The ornamental design for a combined lip balm and floss container with caps on both ends, as shown and described.

DESCRIPTION

This application claims the benefit of Lip Balm and Floss Container, Application Ser. No. 29/614,332 (Application No. '332), filed on Aug. 17, 2017. This application is a Continuation-In-Part of the '332 Application.

FIG. 1 is an upper back perspective view of a combined lip balm and floss container with caps on both ends.

FIG. 2 is a right side perspective view of the combined lip balm and floss container with caps on both ends as shown in FIG. 1.

FIG. 3 is a front view of the combined lip balm and floss container with caps on both ends as shown in FIG. 1.

FIG. 4 is a back view of the combined lip balm and floss container with caps on both ends as shown in FIG. 1.

FIG. 5 is a right side view of the combined lip balm and floss container with caps on both ends as shown in FIG. 1.

FIG. 6 is a left side view of the combined lip balm and floss container with caps on both ends as shown in FIG. 1.

FIG. 7 is a top view of the combined lip balm and floss container with caps on both ends as shown in FIG. 1; and, FIG. 8 is a bottom view of the combined lip balm and floss container with caps on both ends as shown in FIG. 1.

1 Claim, 8 Drawing Sheets
